UNITED STATES PATENT OFFICE

104,522

DESIGN FOR A COMBINED ERASER AND PENCIL TIP

Frank H. Beck, Shelbyville, Tenn.

Application March 18, 1937, Serial No. 68,303

Term of patent 7 years

To all whom it may concern:

Be it known that I, Frank H. Beck, a citizen of the United States, residing at Shelbyville, in the county of Bedford and State of Tennessee, have invented a new, original, and ornamental Design for a Combined Eraser and Pencil Tip, of which the following is a specification, reference being had to the accompanying drawing, forming part thereof.

The figure is a view in perspective of a combined eraser and pencil tip embodying the design.

I claim:

The ornamental design for a combined eraser and pencil tip, as shown.

FRANK H. BECK.
